UNITED STATES PATENT OFFICE

JOHN J. N. VAN HAMERSVELD, OF CLEVELAND HEIGHTS, OHIO, ASSIGNOR TO THE WARNER AND SWASEY COMPANY, OF CLEVELAND, OHIO, A CORPORATION OF OHIO

WAY-GUARD CONSTRUCTION FOR MACHINE TOOLS

Application filed October 18, 1926. Serial No. 142,719.

This invention relates to a way guard construction for machine tools having one or more sliding members supported on ways, at least one of which is common to the sliding members if a plurality of sliding members are employed.

In U. S. Patent No. 1,575,735, granted in the names of E. P. Burrell and myself, a very practical and effective way guard construction is shown, each way which is common to both sliding members being completely housed in a guard which thus protects the way against injury from falling objects as well as prevents the entrance of chips, dirt, cutting compound and the like onto the surface of the way.

The present invention has for its object to provide a simplified way guard construction and one which can be produced and applied at less cost. A further object is to provide a practical way in which a stationary guard may be applied and supported, which guard, while not completely housing the way, serves to protect it from injury by falling objects and gives a measure of protection against the lodging of chips, dirt and the like on the surface of the way.

The invention may be briefly summarized as consisting in certain novel details of construction and combinations and arrangements of parts which will be described in the specification and set forth in the appended claim.

In the accompanying sheets of drawings showing the preferred form of the invention, Fig. 1 is a side elevation of the major portion of a turret lathe equipped with the invention; Fig. 2 is a plan view of the same with a part of the head in section and some parts unessential to the invention omitted; Fig. 3 is a transverse sectional view substantially along the line 3—3 of Fig. 2; Fig. 4 is a transverse sectional view substantially along the line 4—4 of Fig. 2; and Fig. 5 is a fragmentary view, partly in section and partly in elevation, showing how the stationary guard is supported at the front and rear ends thereof.

Referring now to the drawings, 10 represents the bed which is provided with a head

11 and with ways 12 for two sliding members consisting, in this instance, of a cross slide carriage 13 and a turret saddle 14, the former being provided with a cross slide 15 and the latter with a turret 16. The cross slide and turret may be operated by the usual mechanisms and the spindle (not shown) of the head is shown as provided with the usual rotating work holding chuck 17.

In this instance, the bed is provided with two V-shaped ways although the invention may be employed with ways which are flat or otherwise shaped, and in this instance both ways are common to the sliding members 13 and 14. However, it is not essential that both ways be common to both sliding members, for in some instances only one of the two ways at the top of the bed is common to both sliding members, in which event one of the sliding members, generally the cross slide carriage, is supported on one of the upper ways and on a lower way extending along the lower front side of the bed, as clearly shown in the Burrell and Van Hamersveld patent referred to above. To protect the ways 12, stationary way guards 18 are employed which are preferably stamped from sheet metal of suitable gauge and extend lengthwise of the ways a suitable distance above the same so as to provide between the ways and the guards, except at their front and rear ends, a clearance adapted to accommodate the way engaging portions of the sliding members. These way guards are preferably provided with horizontal portions along the center line and being tapered downwardly along both sides so as to conform somewhat to the shape of the ways, and in this instance the guards slightly overhang the ways, as best indicated in Fig. 3.

At their forward and rear ends, the guards 18 rest upon supports 19, to which they are secured by screws 20. These supports constitute raised portions of the bed in line with the ways 12, but projecting upwardly above the same, and at the top these supports 19 conform to the shape of the under side of the way guards.

Both sliding members are provided with clearance openings 21 for the guards, these openings preferably conforming to the shape

or contour of the guards. Additionally, one and preferably both sliding members serve to support the guards between their ends, and this is accomplished by causing the guards 5 to have sliding engagement with the sliding members where they pass through the same. I now regard it as preferable that the lower surface of the guards only have sliding engagement with the sliding members 13 and 10 14, but, if desired, both the top and bottom surfaces of the guards may engage the walls forming the openings 21. In Fig. 3 I have 15 illustrated the supporting relation between the guards and one of the sliding members, and this view will suffice for showing the supporting relation between the guards and the other sliding member.

Thus it will be seen that though stationary guards are provided extending the length of 20 the ways, the movement of the sliding members toward and from each other and toward and from the head is not interfered with, and, furthermore, it is to be noted that with this construction there is ample stock in the 25 sliding members above the ways for firmly and rigidly supporting the sliding members, and by supporting the guards on the bed at their forward and rear ends only and supporting them between their ends on one or both 30 of the sliding members, the guards are amply supported and are capable of withstanding, without deformation or bending, severe blows to which they may be subjected.

While I have shown the preferred construction, I do not wish to be confined to the 35 precise details shown but aim in my claim to cover all modifications which do not involve a departure from the spirit and scope of my invention.

40 Having thus described my invention, I claim:

In a machine tool, a bed having a way, one or more slideable members movable thereon, a stationary guard over the way and extending 45 through an opening in each slideable member, said guard having downwardly inclined sides, and supports on the bed for opposite ends of the guard, the base of the opening of each slideable member and the upper ends 50 of said supports conforming substantially to the transverse contour of the guard and being engaged by the lower surface of the guard for substantially the width thereof.

In testimony whereof, I hereunto affix my 55 signature.

JOHN J. N. VAN HAMERSVELD.
